UNITED STATES PATENT OFFICE.

ELWOOD N. CORNELL, OF HEMPSTEAD, NEW YORK, ASSIGNOR TO THE MIDDLETON SILVER COMPANY, OF MIDDLETON, CONNECTICUT, A CORPORATION OF CONNECTICUT.

DESIGN FOR A POT OR SIMILAR ARTICLE.

Application filed March 17, 1928. Serial No. 25,896. Term of patent 3½ years.

To all whom it may concern:

Be it known that I, ELWOOD N. CORNELL, a citizen of the United States, residing at Phoenix Street, Hempstead, county of Queens, and State of New York, have invented a new, original, and ornamental Design for a Pot or Similar Article, of which the following is a specification, reference being had to the accompanying drawing, forming part thereof.

I claim:

The ornamental design for a pot or similar article as shown.

ELWOOD N. CORNELL.
